UNITED STATES PATENT OFFICE

LLEWELYN WYNN-WILLIAMS, OF DARLINGTON, ENGLAND

RAILWAY-SWITCH MECHANISM

Application filed March 14, 1929, Serial No. 347,086, and in Great Britain February 14, 1929.

The invention relates to railway switch mechanism of the kind in which the switch rails are resiliently supported upon anti-friction bearings, so as to be normally lifted and 5 readily movable but resting firmly upon rail bearing plates or chairs when depressed by a train passing thereover.

The object of the present invention is to provide improved means of this kind which 10 will possess great durability and safety of action when in use, and which will be easily operated, whilst the cost of maintenance will be reduced to a minimum.

According to this invention a beam or member having a path or race for a roller carried 15 by the switch rail is provided, and said beam or member which extends transversely beneath the running rails is suspended or supported by means fixed to said running rails, 20 and the roller is mounted in a bearing carried by a bracket or holder carried by the movable switch rail, the arrangement being such that the roller traverses the race or path 25 of said beam or member at the same time supporting said movable switch rail.

The invention also includes other features which will be apparent from the following detailed description illustrated by the accompanying drawings, in which: Figure 1 is 30 an elevation of railway switch mechanism constructed according to the present invention. Figure 2 is a detail view of the arrangement of mechanism at one end of the beam. Figure 3 is a plan of one end of the beam separately illustrating one form of construction thereof. Figure 4 is a view similar 35 to Figure 2 illustrating a modification. Figure 5 is a view similar to Figure 3 illustrating means fixed to the beam for providing a path or race for the roller. Figure 6 is a side elevation of one end of the beam illustrating modified means for providing a path or race 40 for the roller. Figure 7 is a transverse section thereof. Figure 8 is a plan thereof. Figure 45 9 is a plan of part of the beam when made in sections illustrating means for insulating the adjacent parts, and Figure 10 is a side elevation of part of the switch rail and 50 roller carrying bracket or holder illustrating

means for levelling the roller, the beam being shown in transverse section.

Referring to Figures 1 to 3, which illustrate the application of the invention to flat footed rails, 1 represents the running rails, 55 2 represents the switch rails, 3 represents the beam or member which extends transversely beneath the running rails 1 and which presents a path or race for a roller 4 which supports the switch rail 2, and said roller is 60 mounted in a bracket or holder carried by said switch rail 2, as hereinafter described.

The parts hereinafter referred to are described as applied to one end of the beam, but it will be understood that an identical arrangement of such parts is provided at each 65 end of the beam 3.

The beam 3 is furnished with an eye 5, (Figure 3) at each end thereof and one or both of said eyes are formed in an oblong or equivalent shape so as to leave play to allow for any spread in the road and also for any deviation in the distance between the running rails 1. 70

The beam 3 is preferably formed of a bar of iron or steel, or it might be other suitable metal or material, having any suitable section and when of rectangular or equivalent section the eyes 5 may be conveniently constructed by bending or folding back the ends of said bar so as to form said eyes 5, the ends of the 75 bar being run along the body thereof thus doubling the thickness thereof, thereby, besides forming the eyes 5, providing a path or race for the roller 4, said bent over portion or end of the beam being fixed to the body of 80 the beam by means of rivets 3^a, or they might be bolts and nuts, this construction of the beam 3 being more particularly illustrated 85 at Figure 3.

The eyes 5 or the beam 3 might be constructed or made otherwise than in the manner hereinbefore described. 90

For instance, the beam 3 might be of T, channel or equivalent section, and the eyes 5 may be punched or pressed out of the metal 95 or material of which the beam is made, as will be readily understood.

The beam 3 is suspended from the running rails 1 by the following means.

6 represents vertical bolts or rods which at 100

their lower end engage in the eyes 5 of the beam 3, and are there formed of rectangular or equivalent section to prevent the same turning or rotating in said eyes 5 when the 5 nuts hereinafter referred to are tightened or slackened in order to adjust the spring, as hereinafter described.

7 represents a bracket, preferably an L shaped bracket, as shown, one arm of which is bolted to the running rail 1 by means of a bolt and nut 8 and the surface of said bracket 7 which abuts the rail 1 is formed curved or concave in order to prevent the rocking thereof. The other arm of said bracket is horizontally disposed, or approximately so, and is perforated, the bolt 6 passing through said perforation.

The extreme lower end of the bolt 6 is provided with an enlargement 9 upon which the beam 3 rests, as shown in Figures 1 and 2, and screwed upon the upper end of the bolt 6, which is threaded for that purpose, is a nut 10 between which and the bracket 7 is interposed a spring 11 which embraces the bolt 6, the arrangement being such that the beam 3 is resiliently suspended from the bracket 7 by the bolt 6 through the medium of the spring 11 and nut 10. A lock nut 10^a is also provided to prevent the nut 10 loosening 20 through vibration, or other suitable means might be provided for that purpose.

The switch rail 2 is supported on a roller 4 which, when the rail 2 is moved, moves over or traverses the beam 3 to the extent of 25 the movement of said switch rail 2.

The roller 4 is mounted in ball bearings 12 (which, however, might be dispensed with as will be readily understood) in a holder or bracket 13 provided with a vertical pin or shank 14 which projects through a hole or perforation in the foot 2^a of the switch rail 2, a key or plate 15 being inserted between the foot 2^a of the rail 2 and the upper surface of the holder or bracket 13 in order to lock the same against rotary movement and keep the roller 4 at right angles to the path or race on the beam 3. Or said member 15 may be formed integral with the bracket or holder 13 instead of being separate therefrom. It will, 30 however, be understood that it is preferred to construct the member 15 as a separate member, inasmuch as when wear takes place, said separate member 15 can easily be bent or adjusted by the blow of a hammer on the right spot, or said separate member 15 could be very easily replaced.

When constructed as a separate member, said member 15 comprises a plate having one end or side bent upwardly so that it bears 35 against the edge of the foot 2^a of the switch rail 2, and the other end is bent downwardly so that it bears against the roller bracket 13, as will be understood upon reference to Figure 2.

55 In the example given at Figure 4 are illus-

trated modified means for fixing the holder or bracket 13 to rails other than flat footed rails.

In this case the shank or pin 14 is dispensed with and in lieu thereof the holder or bracket 13 is provided with an upwardly extending arm or plate 16, preferably a plate integral with the roller carrying holder or bracket 13, as shown, which is bolted to the web of the rail 2 by means of a bolt and nut 17, said arm or plate 16 being cranked or shaped in such manner as to accommodate the foot 2^a of the rail 2, which rests upon the roller holder or carrier 13 as hereinbefore described.

Thus by this construction a combined plain or ball bearing roller bracket or holder and switch rail bracket is provided. In other respects the device is identical with that hereinbefore described.

It is desirable that the part of the beam 3 on which the roller 4 bears, be hardened to give greater durability, but it is not practicable to harden or case harden the beam 3 itself, as that would tend to warp the same. 90 In order therefore to provide a hardened path for the roller 4, the beam 3 is provided with separate members constituting paths or races for each roller 4 thereover, which races are fixed to the beam in any suitable manner and which members can be previously case hardened so as to give the desired durability.

One form of construction for attaining this end is illustrated in Figure 5, wherein 100 18 represents such a member which in this case consists of a block of iron or steel, or other suitable metal or material, located between the turned back part of the beam and the body of the beam itself and fixed by the bolts or rivets 3^a, hereinbefore referred to, the member 18 being perforated to receive the same, and said member 18 may be case hardened upon its upper surface for the purpose hereinbefore described.

In Figures 6, 7 and 8 this construction is modified. In this case the member 18 is of T section, the horizontal limb or part of the T being case hardened and resting upon the top surface of the beam 3 thus providing a 115 path for the roller 4 and the vertical limb or part 18^a being perforated and fixed in position between the turned back part of the beam 3 and the body of the beam itself, and fixed by the bolts or rivets 3^a as shown.

In some cases the beam 3 as shown in Figure 9 may be made in two halves which overlap one another where they meet and are bolted together by bolts and nuts 19, whilst between said overlapping parts fibre or other 125 suitable packing 20, preferably electrically insulating packing or fibre, is inserted which construction is suitable for use in cases where the rails are track circuited.

130 In the example given at Figure 10 is il-

lustrated means for levelling the roller 4 with its path or race on the beam 3, which means consist in providing the holder or bracket 13 with a curved surface 13^a at that 5 part on which the switch rail 2 bears, the hole in the foot 2^a of the rail 2 being somewhat enlarged, as shown, to allow the requisite play when the bracket or holder 13 rocks, and to assist to this end the spindle of the roller 4 is mounted in slots 13^b in the bracket 13 by which means it is ensured that the roller 4 rolls on its path or race in such manner as to transmit the pressure uniformly 10 to the surface of said path.

15 This construction of the bracket 13 is similarly applicable to rails other than flat footed rails when the shank 14 takes the form of an upwardly extended plate which is bolted to the web of the switch rail 2, as hereinbefore 20 described.

25 It will be understood that the details of construction of the railway switch mechanism hereinbefore described may be modified according to requirements without departing from the principle of the invention.

I claim:

1. Railway switch mechanism comprising a pair of running rails, a beam extending transversely beneath said running rails, 20 means for suspending said beam from said running rails, movable switch rails, rollers carried by said movable switch rails, means for carrying said rollers, and races on the beam over which said rollers traverse when 25 the switch rails are moved, and means carried by the beam adapted for compensating for the spreading of said running rails.

2. Railway switch mechanism comprising a pair of running rails, a beam extending 20 transversely beneath said running rails, means fixed to said running rails for resiliently adjustably suspending said beam, at each end thereof, movable switch rails, supporting rollers carried by said movable 45 switch rails adapted to traverse said beam, races on said beam for said rollers, brackets in which said rollers are revolvably mounted, means for mounting said brackets on said movable switch rails, and means carried by 50 said beam adapted for compensating for the spreading of the running rails.

3. Railway switch mechanism comprising, a pair of running rails, a beam extending transversely beneath said running rails, 55 brackets fixed to said running rails, adjustable means for suspending said beam from said brackets, movable switch rails, brackets fixed to said movable switch rails, rollers revolvably mounted in said brackets, paths on 60 said beam adapted to be traversed by said rollers when the switch rails are moved, and means for fixing said brackets to said movable switch rails, and means carried by said beam adapted for compensating for the 65 spreading of the running rails.

4. Railway switch mechanism comprising, a pair of running rails, a beam disposed transversely beneath said running rails, brackets fixed to said running rails, vertically disposed bolts suspended from said brackets, 70 means carried by said bolts for supporting said beam, eyes in said beam through which said bolts pass, movable switch rails, brackets fixed to said movable switch rails, a pin carried by said brackets, perforations in the 75 feet of the switch rails through which said pins pass, ball bearing rollers mounted in said brackets, paths on said beam adapted to be traversed by said rollers when the switch rails move, and means for maintaining the 80 axes of said rollers at right angles to said paths.

5. Railway switch mechanism comprising a pair of running rails, a beam suspended transversely beneath said running rails, L 85 shape brackets bolted to said running rails, perforations in said brackets, vertical bolts passing through said perforations, enlargements on the lower ends of said bolts, elongated eyes in said beam through which said bolts pass, means for preventing rotation of said bolts, nuts screwed on the upper ends of said bolts, springs interposed between said nuts and said brackets, said beam resting on said enlargements, movable switch rails, 95 rollers carried by said movable switch rails and paths fixed to said beam, said rollers supporting the switch rails and traversing said paths when the switch rails are moved.

6. Railway switch mechanism comprising a pair of running rails, a beam extending transversely beneath said running rails, means for adjustably resiliently suspending said beam from said running rails, means carried by said beam adapted for compensating for the spreading of said running rails, 100 movable switch rails, brackets fixed to said movable switch rails, rollers carried by said brackets, paths on the beam for said rollers, means on said brackets for levelling said rollers to press evenly on said paths and plates for maintaining the axes of said rollers at right angles to said paths.

7. Railway switch mechanism comprising a pair of running rails, a beam extending transversely beneath said running rails, means for suspending said beam from said running rails, eyes in said beam, said eyes being made by folding back the beam upon itself and riveted thereto, movable switch rails, 115 roller carrying brackets, perforations in the feet of the movable switch rails, shanks carried by said roller carrying brackets located in said perforations, key plates interposed between said roller carrying brackets and the 120 feet of the movable switch rails, projections on said plates engaging the feet of the switch rails, projections on said key plates engaging the roller carrying brackets for preventing the turning of said roller carrying brack- 125 130

ets, rollers mounted in said brackets, paths on the beam for said rollers and means for levelling said rollers with said paths.

8. In railway switch mechanism as claimed in claim 1, a transversely divided beam, the parts overlapping and bolted together, any suitable insulating fibre being interposed between said meeting parts.
